UNITED STATES PATENT OFFICE.

EDWARD POHL, OF NEW YORK, N. Y.

PROCESS OF BURNING FUEL.

1,210,099.

Specification of Letters Patent. Patented Dec. 26, 1916.

Application filed February 2, 1916. Serial No. 75,774.

To all whom it may concern:

Be it known that I, EDWARD POHL, a citizen of the United States, residing at the city of New York, in the borough of Manhattan and State of New York, have invented certain new and useful Improvements in Processes of Burning Fuel, of which the following is a full, clear, and exact description.

This invention relates to a process for utilizing as a heating medium, a fuel which slowly gives off inflammable vapors at ordinary temperatures. One of such fuels is "solidified" alcohol, which is a compound having for its essential constituents stearic acid and alcohol, the compound forming a solid at ordinary temperatures. Alcohol in this form is admirably suited for use as a heating medium in households and other places where there is a likelihood of a liquid spilling, as well as providing a form of alcohol which is adapted to be sold to the retail trade for heating purposes. Heretofore it has been the usual practice to sell "solidified" alcohol in a can similar to a paint can having an open top provided with an air-tight cover, the alcohol being utilized by removing the cover and igniting the inflammable vapors which slowly rise from the surface of the body of the fuel within the receptacle. However, it has been found that this method of burning the alcohol is not efficient, nor does it produce intense heat for the reason that the air does not come into intimate contact with all portions of the combustible vapor, the result of which is incomplete combustion.

The object of my invention is to provide a new method or process of burning a fuel which gives off inflammable vapors at ordinary temperatures, which method is particularly adapted for use with solidified alcohol, and in carrying out my improved method or process, I make use of the well-known theory that if a fuel, either liquid or solid which gives off an inflammable vapor, is heated, then the vaporization will take place more rapidly which permits the collection of the vapor in a closed chamber under pressure, after which the vapor may be divided into streams and passed through a burner so that when it is ignited, a more intimate mixture of the vapor and air will be obtained, which will produce a more intense heat, as well as providing a more economic consumption of fuel. The fact that the vapor is

under pressure may also be utilized to direct the flames against the surface to be heated. In so far as I am aware, this method of burning fuel has been utilized with heaters where an additional burner is provided to heat the fuel to cause the rapid evaporation of the inflammable vapor. While such a burner can be provided with a liquid fuel, which burner may be supplied from the same source as the main burner, yet with a solid fuel, such as solidified alcohol, an additional burner fed from the same source of fuel is an impractical if not an impossible, construction.

My improved method therefore, has for its purpose the elimination of this additional burner and comprises burning the inflammable vapors which rise from the surface of the fuel for a sufficient period of time to enable a portion of the heat generated in this manner, to heat the body of the fuel and cause a more rapid evaporation of the fuel. When evaporation is taking place at a relatively rapid rate, the flame from the surface of the body of the fuel is extinguished and simultaneously therewith the vapor, which is now being rapidly given off by the fuel, is collected and burned in independent jets at points removed from the surface of the body of the fuel. A portion of the heat from these burning jets is also utilized to heat the body of the fuel so that the vaporization of the same will continue at the same or at a more rapid rate.

More specifically stated, the method consists in placing the fuel in an open container having heat-conducting walls in which the surface of the body of the fuel within the container is exposed to the atmosphere and the vapor rising from this exposed surface is burned for a period of time sufficient to cause a portion of the heat to be transmitted to the walls of the container to heat the body of the fuel and to cause it to vaporize at a more rapid rate. This flame is then extinguished and the walls of the chamber are simultaneously extended to provide a closed chamber above the fuel. The chamber thus formed is provided with burner openings through which the vapor will then flow in independent jets which will be ignited and burned, the openings being of such a size that a low vapor pressure will be created in the closed chamber. These burning jets are so directed

as to cause a portion of the heat therefrom to impinge upon the walls of the burner and continue to heat the body of the fuel so that the vaporization of the same will be continued.

5 The method described may be carried on with various kinds of apparatus and in the illustrated embodiment herein shown, one specific device which is adapted for this purpose is shown, but it is to be understood that the method or process is in no manner restricted to the apparatus shown.

10 In the accompanying drawings: Figure 1 shows a heater which is adapted for use in practising my improved method; and Fig. 15 2 is a central section through the same, with the auxiliary cover which covers the burner openings removed.

15 The heater comprises a container 1 which 20 as in the usual construction, is formed of a sheet metal and is provided with an open top closed by a dish-shaped cover 2, which, when in place, forms an air-tight joint between the container and cover and prevents 25 any evaporation of the fuel, the container being similar to the usual type of paint can. This can is only partially filled with the fuel which is indicated at 3, and while various 30 kinds of liquid and solid fuels may be used, which give off an inflammable vapor at ordinary temperatures, the invention is particularly applicable to solid fuels, such as "solidified" alcohol.

35 Arranged in the walls of the container above the level of the top of the fuel, are a plurality of restricted burner openings 4. These openings are arranged in the walls of the container so that the jets of flame issuing therefrom will impinge against the walls 40 of the container and a portion of the heat of the burning jets will therefore be transmitted to these walls. The burning openings should be of a size that their combined area is such that the vapor which collects in the 45 closed chamber formed above the body of the fuel when the top is replaced upon the package, is restricted in its passage from the chamber sufficiently to create low vapor pressure within the chamber.

50 In order to prevent the evaporation of the fuel through the burner openings 4 when the heater is not being used, an auxiliary closer 5 is provided having a flange which fits tightly over the upper portions of the 55 side walls of the container and seals the burner openings. The type of heater described is similar to the one described and claimed in my co-pending application Serial No. 75,773, filed February 2, 1916, and is 60 illustrated and described merely for the purpose of showing one type of heater with which my improved method may be practised, which will now be described in connection with the embodiment shown.

65 When it is desired to burn the alcohol,

both covers 2 and 5 are first removed, which will expose a portion of the surface of the body of the fuel within the container to the atmosphere, and an inflammable vapor will therefore be slowly given off from the surface of the body of the fuel. This vapor is ignited and burns in a single flame of a relatively large size. So far the method is similar to the method employed with the type of heaters at present on the market for this 70 character of fuel. The heat of this flame from the surface of the body of the fuel is transmitted to the annular ring or top which supports the cover and within a comparatively short time, say, from fifteen seconds 75 to a minute and a half, a portion of the solidified alcohol within the container will be melted and evaporation will take place much more rapidly. When this occurs, the cover 2 is replaced upon the container, which 80 extinguishes the flame rising from the surface of the body of the fuel and if the evaporation of the fuel is taking place at a relatively rapid rate, sufficient vapor will collect in the closed chamber above the surface 85 of the fuel, which is formed by replacing the cover 2 to flow outwardly through the burner openings 4 where it is ignited and burned in a plurality of independent jets. These jets of flame since the burner openings in the form shown are in the side walls 90 of the container, curve around and impinge against the upper end portions of the side walls of the container and will therefore 95 heat both the container and its top, which heat will be conducted to the body of the fuel and cause a further evaporation of the fuel to produce an inflammable vapor, which vapor collects in the closed chamber as before described and flows out through the 100 burner openings, where it is burned.

One of the important features of the process described is that the heat developed remains as great even after the volume of fuel in the container has been materially decreased. This is true because the vapor is only burned at the surface of the fuel during the initial steps of the process, while at all other times the vapor from the surface of the fuel rises and flows out through the 110 burner openings which remain at a fixed distance from the article to be heated, and since the evaporation of the fuel continues until it is entirely consumed, the burning jets will give as much, if not a greater 115 amount of heat until the fuel is entirely consumed.

I claim:

1. The process of producing heat from a liquid or solid fuel which vaporizes slowly 125 at ordinary temperatures and gives off an inflammable vapor, which consists in burning the vapor at an exposed surface thereof and causing a portion of the heat generated to heat the fuel and increase its rate of va- 130

porization, then extinguishing the flame from the surface of the fuel and inclosing the entire quantity of collecting vapor given off by the fuel, then burning the collecting vapor in a plurality of independent jets directed to impart heat to the fuel.

2. The process of burning a fuel which slowly gives off an inflammable vapor at ordinary temperatures, which consists in igniting and burning the vapor at an exposed surface of a body of the fuel contained in an open receptacle having heat-conducting walls, until the heat communicated to the walls sufficiently heats the body of the fuel 15 to cause a rapid evaporation thereof, then extending the walls of the receptacle to form a closed chamber above the body of the fuel and simultaneously extinguishing the flame from the surface of the body of the fuel, and 20 finally burning the vapor collecting in the closed chamber in a plurality of independent jets while causing the heat therefrom to heat the walls of the receptacle and the body

of the fuel to cause a continued rapid evaporation of the fuel.

3. The process of producing heat from a liquid or solid fuel which vaporizes slowly at ordinary temperatures and gives off an inflammable vapor, which consists in burning the vapor at an exposed surface thereof and causing a portion of the heat generated to heat the fuel and increase its rate of vaporization, then extinguishing the flame from the surface of the fuel and inclosing the entire quantity of collecting vapor given off by the fuel under pressure, then burning the collecting vapor under pressure in a plurality of independent jets directed to impart heat to the fuel.

In witness whereof, I subscribe my signature, in the presence of two witnesses.

EDWARD POHL.
